United States Patent Office.

MARTIN LANDENBERGER, OF PHILADELPHIA, PENNSYLVANIA.

Design No. 4,232, dated July 19, 1870.

DESIGN FOR KNITTED GOODS.

The Schedule referred to in these Letters Patent and making part of the same.

To all whom it may concern:

Be it known that I, MARTIN LANDENBERGER, of Philadelphia, in the county of Philadelphia and in the state of Pennsylvania, have invented a certain new and useful Design for Knitted Cloth; and do hereby declare that the following is a full, clear, and exact description thereof, reference being had to the accompanying drawing and to the letters of reference marked thereon making a part of this specification.

The design for knitted cloth is shown in the annexed drawing.

Figure 1 shows a rear view of the fabric.

Figure 2 shows the position of the thread of the fabric; and

Figure 3 represents the front of the fabric and the design claimed.

In figs. 2 and 3, it will be seen that the lines B are at a short distance, where they meet lines A, which are straight. From thence they take an upward oblique turn, and connect again with the upper straight lines A.

C represents the body of the cloth proper.

D D' represent two zigzag lines passing across the cloth, with a zigzag line, x, between them, differing from that (in color) of the lines D D'.

Directly above the upper zigzag line D, on the portions thereof that incline downward, are two short strips, z and y, placed one above the other, and of colors differing from each other and the line D.

Directly beneath the lower zigzag line D' are two corresponding strips, y' z', placed under the portions that incline upward.

The cloth may be made of any colors.

What I claim is—

The design for knitted cloth herein shown and described.

In testimony that I claim the foregoing, I have hereunto set my hand this 21st day of May, 1870.

MARTIN LANDENBERGER.

Witnesses:

J. M. MASON,
C. L. EVERETT.
